Primary Examiner — Ania Aman(74) *Attorney, Agent, or Firm* — Dinsmore & Shohl LLP(57) **CLAIM**The ornamental design for a manifold, as shown and
described.

DESCRIPTION

FIG. 1 is an upper perspective view of a manifold showing
our new design;

FIG. 2 is a lower perspective view of the design of FIG. 1;

FIG. 3 is a top view of the design of FIG. 1;

FIG. 4 is a bottom view of the design of FIG. 1;

FIG. 5 is a first side view of the design of FIG. 1;

FIG. 6 is a second side view of the design of FIG. 1;

FIG. 7 is a front view of the design of FIG. 1; and,

FIG. 8 is a rear view of the design of FIG. 1.
